FIG. 1

FIG. 2

FIG. 3

FIG. 4

FIG. 4

FIG. 5

FIG. 1 is a perspective view of a radiographic apparatus for X-raying infants showing our new design;

FIG. 2 is a rear elevation view thereof;

FIG. 3 is a side elevation view thereof;

FIG. 4 is a perspective view of the apparatus of FIG. 1 showing the front door of the X-ray chamber open and the X-ray source in an external position to enable X-raying of an infant outside of such chamber; and

FIG. 5 is a perspective view of another embodiment of the invention which is similar to the apparatus of FIG. 1 but includes bellows adjustment means for attaching the opposite ends of the X-ray chamber to the apparatus.

We claim:

The ornamental design for a radiographic apparatus for X-raying infants, as shown and described.
